Primary Examiner — Katrina A Betton

(74) Attorney, Agent, or Firm — Burr & Forman LLP;
Douglas L. Lineberry(57) **CLAIM**

The ornamental design for a connector hitch, as shown and described.

DESCRIPTION

FIG. 1 is a back side perspective view of the connector hitch;
 FIG. 2 is a front view of the connector hitch;
 FIG. 3 is a back (rear) view of the connector hitch;
 FIG. 4 is a left view of the connector hitch;
 FIG. 5 is a right view of the connector hitch;
 FIG. 6 is a top view of the connector hitch;
 FIG. 7 is a bottom front view of the connector hitch; and,
 FIG. 8 a left view of the connector hitch with the forward
 piece rotated and dashed to show position of the forward
 place is not being claimed.

The broken lines shown in the drawings are for illustrative
 purposes and form no part of the claimed design.
